97,350

DESIGN FOR A MOLDING FOR PIECES OF FURNITURE

Clarence G. Kimerly, Grand Rapids, Mich.

Application July 5, 1935, Serial No. 57,523

Term of patent 3½ years

To all whom it may concern:

Be it known that I, Clarence G. Kimerly, a citizen of the United States, residing at 1500 Robinson Rd., S. E., Grand Rapids, in the county of Kent and State of Michigan, have invented a new, original, and ornamental Design for a Molding for Pieces of Furniture, of which the following is a specification, reference being had to the accompanying drawing, forming a part thereof, in which:

Figure 1 is a perspective view of a molding showing my design, the distinguishing, essential and dominating feature or characteristic of the design being the motif per se which is shown in full lines, the horizontal, vertical and lateral dimensions of the molding being shown in dotted

lines and indicating unimportant features of the design since the motif is adapted to be used in the manufacture of numerous pieces of furniture, as for example, with tables, dressers, beds, mirror frames, chairs and the like;

Figure 2 is an enlarged detail view of the elements forming the motif per se; and

Figure 3 is an enlarged fragmentary side elevational view of the elements forming the motif per se, the dotted lines indicating unimportant features of the design.

I claim:

The ornamental design for a molding for pieces of furniture as shown and described.

CLARENCE G. KIMERLY.
